RADIO OBSTACLE LOCALIZING APPARATUS

René Jean Hardy, Lyon, France, assignor to International Standard Electric Corporation, New York, N. Y.

Application March 7, 1941, Serial No. 382,152

7 Claims. (Cl. 250—11)

The present invention relates to direction finding systems and particularly to radiogoniometers and obstacle radio localizing apparatus.

An object of the invention is to provide radio direction finders giving instantaneous indications of directions without the use of any rotating element for the search of said directions.

Another object of the invention is to provide a radio obstacle direction finder giving simultaneous and instantaneous indications of the directions of a plurality of obstacles.

Another object of the invention is to improve the accuracy and the stability in time of radio direction finders.

More specifically, an object of the invention is to provide a radio direction finder which is able to operate as a panoramic obstacle localizing apparatus giving instantaneous and simultaneous indications of directions.

According to some features of the invention, a radiogoniometer comprises a wave collector having crossed diagrams of reception and associated to an omnidirectional antenna adding algebraically a constant phase energy to each energy of said diagrams, two radio receivers supplied from said collector with the respective energies from said diagrams and an indicator such as an oscilloscope the deflection circuits of which are respectively connected to said radio receivers, means for automatically correcting gain differences between said radio receivers and means for automatically checking the efficiency of this gain regulating arrangement.

According to some features of the invention, an obstacle direction finder comprises a radio pulse generating and transmitting arrangement, a wave collector having two crossed diagrams of reception, and associated to an omnidirectional antenna adding algebraically a constant phase energy to each energy of said diagrams, two radio receivers supplied from said collector with the respective energies from said diagrams and an indicator the deflection circuits of which are respectively connected to said radio receivers, means for automatically correcting gain differences between said radio receivers and means for automatically checking the efficiency of this gain regulating arrangement.

According to another feature of the invention, said checking means comprises an impulse generator and a transmission path for supplying periodically these short pulses to the inputs of said radio receivers, so that a luminescent indication of the reference line will periodically appear on the screen of the indicating oscilloscope.

According to another feature, the transmission path for checking the regulating action of the gains of said radio receivers comprises a spatial path from a transmitting aerial energized by a pulse transmitter and arranged in front of the wave collector, to said wave collector.

These objects and features, as well as others, will now be described in details in the following specification based upon the attached drawings, in which:

Figure 1 represents diagrammatically an embodiment of a radiogoniometer or of an obstacle direction finder, according to certain features of the invention;

Figure 2 shows a wave train such as transmitted from the transmitting aerial of the arrangement of Figure 1;

Figure 3 shows the transmitted pulse or wave train and return pulses after reflection upon obstacles in the space around the direction finder;

Figure 4 shows an example of simultaneous indications which may appear on the screen of the oscilloscope in the embodiment of Figure 1;

Figures 5 and 6 show diagrammatically circuit arrangements embodying a feature of the invention used in the embodiment of Figure 1; and

Figure 7 shows a diagram relating to the indication obtained upon the screen of the oscilloscope of Figure 6.

Referring now to Figure 1 of the attached drawings, a wave collector comprises two crossed elements C₁, C₂, which may consist of loops, frames, antennae or any other suitable collectors having crossed diagrams of reception. The elements of said wave collector are connected respectively to two radio receivers R₁, R₂. These receivers are of such structure that, connected by a well-known coupling circuit N which applies the output of the receivers to separate opposite deflecting electrodes of the deflection systems, for example the deflecting plates, of a cathode ray oscilloscope, they produce a scanning of the cathodic spot controlled by the differences of the currents received in each of the collecting elements C₁, C₂. Thus, if, by means of a transmitting aerial placed along the axis Z', i. e. along the bisector plane of the wave collectors C₁, C₂, a short duration high frequency pulse is transmitted, the receivers R₁, R₂ will receive with equal strength said transmitted signal and the luminescent spot S on the screen of the oscilloscope normally at the center O will be deflected with an equal strength by the two plates P_x, P_y or other deflecting elements, in the direction O_T. When said signal is received by the collectors

C1, C2 the spot goes towards A and arrives at A when the wave train has its maximum amplitude and comes back to O when the wave train is passed. This luminescent line OA, very rapidly produced, may be repeated a great number of times if a great number of short pulses is received. In the case where the received signal is of constant amplitude, the spot S will be steadied at A or at any other point of line OT depending on the signal strength.

When the received signal is of constant amplitude, in order to obtain a luminescent line on the screen, it will be sufficient to effect a radial modulation of the cathode beam, for example by superimposing on the anodic voltage of the tube an alternating voltage which will effect this radial modulation. Any other suitable arrangement for modulating radially the cathodic beam may be in fact utilised.

If the wave collector as a whole, C1, C2, is now rotated so as to present a line of optimum reception different from the ZZ' axis, i. e. is rotated around point Z, the line OT on the screen will come at OT', for example. This type of circuit provides in this way a manually rotatable goniometer enabling the finding of the direction of propagation of a radioelectric source of waves. In fact, if the wave collectors C1, C2 are fixed and if the distant transmitter lies in a direction different from Z, Z', an effect similar to that described for line OT will be obtained and the luminescent line OT' will indicate the direction of said transmitter.

The operation of the portion of Figure 1 already described will be better understood with reference to Figures 5 to 7 which will now be described.

In Figure 5, is schematically shown an example of embodiment of one of the paths from the collector, let it be C1, constituted by two windings L1, L2 through the receiver R1 and the coupling circuit N to a pair of deflecting plates Px, Px' of the oscilloscope I.

The windings L1, L2 are the two halves of a frame collector placed into the field of a distant radiotransmitter E the direction of propagation of which makes an angle α with the plane of said frame, said windings L1, L2 having their outputs respectively connected to the grids of amplifying valves V1, V2, the output circuits of which are then connected through transformers T1, T2 to detectors D1, D2. The D. C. voltages at the outputs of D1, D2 would be identical if, according to a feature of the invention, the current from an omni-directional or vertical antenna A2 were not applied by an inductive coupling L upon the two windings L1, L2, in opposite directions. Said antenna current has a phase in definite relation with the high frequency current received by the windings L1, L2. The phase of the incoming current will be additive to the phase of the current in one winding, L1 for example, and subtractive in the other L2. At D1 and D2, there will be then different voltages and, as these voltages are applied on the control grids of the double triode valve V3 (in the N circuit of Figure 1), the output voltages of which control the deflection of the cathodic spot S, this spot will come to a position, S' for example, different from the center of the screen, which will depend on the angle of the radiotransmitter with the plane of the frame L1, L2, and the direction of this variation on the screen will then be from Px to Px' and vice versa.

If, now, as shown in Figure 6, a second frame

C2, having two windings L3, L4 is perpendicularly associated to the frame C1, each frame will be used for supplying deflecting voltages to one pair of perpendicular plates, or other deflecting elements, of an oscilloscope I through radio receivers R1, R2 which may each comprise the circuits shown in Figure 5. The circuit of Figure 6, which, it may be seen, corresponds to a portion of the circuit shown in Figure 1 comprising the wave collector C1, C2, the two radio receivers R1, R2, the coupling or distributing circuit N (valve V3 of Figure 5) and the oscilloscope indicated by the plates Px, Py, operates as a phase indicator giving the angle between the direction of the radiotransmitter E, Figure 5, and a determined direction of reference. The cathodic spot S will be on a circle M and, according to the direction of the radiotransmitter or to the orientation of the wave collector structure, C1, C2, Figure 1, or L1, L2, L3, L4, Figure 6, the angle of the radius upon which rests the cathodic spot will change.

In Figure 7, there is shown the screen of the cathode ray oscilloscope I, on which line OP corresponds to the axis of the horizontal deflecting plates and line OQ to the axis of the vertical deflecting plates. The cathodic spot will always be on a radius OA, the angle α of which with line OQ will depend upon the orientation of the radio transmitter with respect to these axes, and, according to the strength of the detected signal, the spot S will be at a point of line OA such as a , having coordinates q and p .

As mentioned above, according to a feature of the invention, in such direction finding arrangements, the constant phase current from antenna A2 is permanently superimposed on the currents of the windings L1 to L4 of the frames. This markedly increases the high frequency voltage entering into the radio receivers R1, R2 and moreover all this high frequency of constant phase, which enables the complete scanning of the spot along two rectangular diameters and consequently along a whole circumference, does not effectively appear on the cathode ray indicator since the difference only of the high frequency voltages collected on the frames C1, C2 is used for deflecting the cathodic spot.

In order to obtain correct indications of direction, it is necessary to have a great stability of operation and gain of the two radio receivers R1, R2, the circuits of which are provided as identical as practically possible. If the receivers R1, R2 were not identical, when the received signal arrives along the axis Z, Z', Figure 1, this signal would not be amplified the same in the two receivers and the indication obtained would no longer be the line OT but another line, such as OT for example, and all further indications of direction will be erroneous, since this line OT is taken as a direction of reference or zero angle.

Consequently, according to a feature of the invention, a device such as indicated at V is provided. This device automatically corrects the gains of the two receivers and may, for example, consist of a well-known automatic volume control circuit, suitably provided to correct the gain of each receiver according to the gain of the other, as indicated by the cross-connections F.

According to another feature of the invention, means are provided for obtaining a visual check of this gain regulation. Thus, for example, from time to time, the high frequency circuits of the frames C1, C2 are disabled, and, at repeated intervals, a short pulse is sent with equal strength into the high frequency inputs of the two receiv-

ers. These short pulses may be created from an impulse generator D, of any well-known type, creating pulses from the output of a sinusoidal generator G, and brought to the inputs of the receivers by the connection or line K. Automatically, upon the screen of the oscillograph I, will appear a luminescent line which is to be coincident with line OT if the gains of the receivers are of the suitable value, as in the case of the reception of a signal along the line ZZ'. If the gains are not correct, a line such OT' will appear. It will thus be easy to observe the operation of the automatic volume control circuit V. This injection of short pulses into the inputs of the receivers may be provided at a rhythm suitable for obtaining a continuous vision of this gain regulation and this check may be effected by a deflection of the cathodic spot which does not impair the goniometric operation of the complete equipment.

Another process provided in the invention for injecting short pulses into the inputs of the receivers is to arrange an antenna A1 along the axis ZZ' near the wave collector C1, C2, and to energize said antenna by means of a pulse transmitter E controlled by a pulse generating circuit D in order to transmit from time to time a pulse which is passed to the receivers by the collectors C1, C2 and acts as above described for giving an indication of the oscillograph screen.

An arrangement such as shown in Figures 1, 5 and 6, may be used, as described, for the purpose of finding the direction of radio sources, broadcast transmitters or others. It may be used equally as an obstacle direction finder, and in this case, will be able to give simultaneous indications of a number of obstacles on the screen of the oscillograph.

For such an operation, the pulse transmitter E is provided of the necessary power to transmit by its antenna A1 regularly spaced impulses to a distance. Figure 2 shows, as an example, a short duration pulse such as transmitted by antenna A1. This pulse t_0 consists of a series of high frequency oscillations having an envelope curve which increases progressively from zero to a maximum value then back to zero. This wave train t_0 is immediately applied to the wave collector C1, C2 since antenna A1 is placed in close proximity of said wave collector, and along the axis ZZ'. The receivers R1, R2 will then amplify the received energy and on the screen of the oscillograph will give the luminescent line OT. It should be noted that the coincidence of said line OT with a marked direction on the screen will give the desired visual checking of the operation of the automatic volume control circuit V. However, as the difference between the energy of this transmitted pulse and those of the pulses which eventually come back after reflection upon obstacles is very great, as shown for example in Figure 3, by the difference of surfaces between the pulse t_0 and the successively reflected pulses t_1 , t_2 , t_3 , there is need to reduce the sensitivity of the receivers R1, R2 at times when each pulse is transmitted by antenna A1, in order to receive the pulse t_0 with a suitable apparent strength. For this purpose, the pulse generator D, which controls in the pulse transmitter E by controlling the bias of a grid for example, controlling the transmission of a wave train, also supplies in synchronism therewith impulses to attenuation circuits provided in any usual manner for example grid bias circuits in the receiver circuit, according to a feature of the invention. Thus a small portion of the pulse t_0 is able to pass the receivers

and ensures the visual check of the gain regulating arrangement V, instead of being completely eliminated by the usual blocking of the receiver as in ordinary obstacle direction finding equipments. This synchronous supply for controlling attenuation networks may be made either through the connection K, or through a separate connection K' coupled inductively at L' to the mid point of the wave collector or directly from the signal transmitted from antenna A1 to the wave collector C1, C2 or a combination of both as shown in the drawing.

A further connection J is also indicated from the pulse generator D to the automatic volume control circuit V in order to provide a control of an attenuation network, which may be a grid bias network, in this circuit for adjusting the sensitivity of the gain of the receiver.

The pulse t_0 being transmitted into free space, will be reflected by the obstacles surrounding the equipment, for example, by planes moving around a landing field, and at times t_1 , t_2 and t_3 , for example, as shown in Figure 3, echoes will arrive onto the wave collector C1, C2 from different directions. Indications such as shown in Figure 4 at OA, OB and OC, will then simultaneously appear on the screen of the oscillograph, the angles of which with the line OT giving instantaneously the orientations of said obstacles with respect to the axis ZZ'. The values OP and OQ for example in the case of the obstacle along the direction OA correspond to the respective currents in the collectors C1 and C2. If the transmission of pulses by antenna A1 is continuous, the lines OA, OB, OC will move in accordance with the respective motions of the different obstacles to which they correspond.

Such a system of observation of obstacles is obviously based on the fact that the various obstacles are located at different distances. When two obstacles are at the same distance, their reflected pulses will arrive at the same time on the wave collector and will give a mean indication on the oscillograph, consequently an erroneous indication of their direction. However, as generally these obstacles will be of small dimensions with respect to the distances to the equipments, and also, as in the case of planes, are of speedy displacements, there is no practical confusion in the indications obtained.

It is clear that in the preceding description, no details have been given on the known elements used.

It is also clear that the invention is not restricted in the specific embodiments described, but is meant to cover all embodiments making use separately or in combination of the arrangements disclosed in the following claims.

What is claimed is:

1. Obstacle radio direction finder comprising a radio pulse generating and transmitting arrangement, a directive wave collector means having crossed diagrams of reception and an associated omnidirectional antenna coupled to said directive collector means for supplying a constant phase energy added algebraically to the received energy representing each energy of said diagrams, two radio receivers supplied from said collector with the respective energies from said diagrams and said antenna and an oscillograph indicator having the deflection circuits which are respectively connected to said radio receivers, means for correcting gain differences between said radio receivers and means for automatically checking

the operation of this gain regulating arrangement.

2. Direction finding equipment as claimed in claim 1, said gain correcting means comprising an automatic volume control circuit arranged to correct the gain of each receiver according to the gain of the other.

3. Obstacle radio direction finder as claimed in claim 1, wherein said transmitting arrangement comprises an antenna arranged along the reference axis of said wave collector, a space transmission path between said antenna and said wave collector, and means responsive to application of said impulses to said receivers for lowering the sensitivity and gain of said two receivers.

4. Obstacle radio direction finder as claimed in claim 1, wherein said transmitting arrangement comprises an antenna arranged along the reference axis of said wave collector, a space transmission path between said antenna and said wave collector, and means for controlling the sensitivity and gain of said receivers in response to transmitted impulses comprising a conductive transmission path from said generator to said receivers to reduce the sensitivity of said receivers under control of said impulses, and a conductive transmission path from said generator to said gain correcting means to reduce the gain of said receiver under control of said impulses.

5. A radio direction finder comprising a directive collection means having crossed diagrams of reception and an associated omni-directional antenna coupled to said directive collector means for supplying a constant phase energy added algebraically to the received energy representing each of said diagrams, two radio receivers supplied from said collector with the respective energies from said diagrams and said antenna and an oscillograph indicator having deflection circuits, said deflection circuits being respectively connected to said receivers, means for correcting the gain differences between said radio receivers and means for automatically checking the operation of this gain regulating arrangement, said means for checking the efficiency of the gain regulating arrangement comprising an electrical impulse generator and a transmission path for

applying the generated pulses into the two radio receivers in a direction of reference, so that indications created by these pulses appear on the oscillographic indicator of the system.

6. A radio direction finder comprising a directive collection means having crossed diagrams of reception and an associated omni-directional antenna coupled to said directive collector means for supplying a constant phase energy added algebraically to the received energy representing each of said diagrams, two radio receivers supplied from said collector with the respective energies from said diagrams and said antenna and an oscillograph indicator having deflection circuits, said deflection circuits being respectively connected to said receivers, means for correcting the gain differences between said radio receivers and means for automatically checking the operation of this gain regulating arrangement, said means for checking the operation of said gain regulating arrangement comprising an electrical impulse generator and a wire transmission path from said generator to the inputs of said receivers.

7. A radio direction finder comprising a directive collection means having crossed diagrams of reception and an associated omni-directional antenna coupled to said directive collector means for supplying a constant phase energy added algebraically to the received energy representing each of said diagrams, two radio receivers supplied from said collector with the respective energies from said diagrams and said antenna and an oscillograph indicator having deflection circuits, said deflection circuits being respectively connected to said receivers, means for correcting the gain differences between said radio receivers and means for automatically checking the operation of this gain regulating arrangement, said means for checking the operation of said given regulating arrangement comprising an electrical impulse generator, an antenna connected thereto and arranged along the reference axis of said wave collector and a space transmission path from said antenna to said wave collector.

RENÉ JEAN HARDY.
